His Attorney

UNITED STATES PATENT OFFICE

GEORGE W. BAUGHMAN, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY-TRAFFIC-CONTROLLING APPARATUS

Application filed October 29, 1929. Serial No. 403,198.

My invention relates to railway traffic controlling apparatus, and particularly to apparatus of the type wherein apparatus carried on a railway vehicle co-operates with trackway apparatus for controlling the vehicle.

I will describe two forms of railway traffic controlling apparatus embodying my invention, and will then point out the novel features thereof in claims.

10 In the accompanying drawing, Fig. 1 is a diagrammatic view showing one form of railway traffic controlling apparatus embodying my invention. Fig. 2 is a diagrammatic view showing a modification of the apparatus of Fig. 1, and also embodying my invention.

Similar reference characters designate similar parts in each of the two views.

Referring first to Fig. 1, the reference 20 characters 1 and 1^a designate the track rails of a stretch Y of railway track on which a railway vehicle, designated by the reference character V, is moving toward the end A of a section of track which is separated from 25 adjoining portions of stretch Y by means of insulated joints 2. A track transformer T, which is connected across the rails adjacent the exit end A, supplies this section with alternating current. Transformer T is, in 30 turn, supplied with current over wires x and o from a source not shown in the drawing.

Mounted on vehicle V are two laminated iron cores h located over the track rails, respectively, each core being U-shaped and with 35 its legs pointing downwardly, and each core being disposed transversely with respect to the rail. It is apparent, therefore, that when alternating current flows in either rail, part of the magnetic lines of force surrounding 40 such rail will pass through the core which is directly over the rail, and so will induce an alternating potential in any coil which the core may carry. The core h over rail 1^a is wound with a coil a¹, and the core h over rail 1 is wound with a coil a².

45 Coils a¹ and a² are included in a circuit passing from coil a¹, through primary winding 3 of transformer F¹, primary winding 3 of transformer F², and winding a² back to winding a¹. A second circuit passes from

coil a¹, through winding 3 of transformer F¹, a tuning condenser 5, and primary winding 8 of a transformer G back to winding a¹. A third circuit passes from coil a², through primary winding 3 of transformer F², condenser 5, and winding 8 of transformer G back to coil a². Coil a² and the other parts of the third circuit are proportioned exactly the same as the corresponding parts of the second circuit. A fourth circuit passes from secondary winding 4 of transformer F¹, through a condenser 6, and the secondary winding 4 of transformer F² back to winding 4 of transformer F¹.

55 Coils a¹ and a² are so wound on their cores h that, at a given instant, when a potential 60 created in winding a¹ by current flowing in a given direction in rail 1^a is positive at terminal 24 of winding a¹, a potential created 65 in winding a² by current flowing in rail 1 in the direction opposite to that of the flow of current in rail 1^a will be positive at terminal 25 of winding a². It is evident, therefore, that when current flows in opposite directions in rails 1 and 1^a, the potentials 70 created in windings a¹ and a² oppose each other. When the potentials thus created in coils a¹ and a² are exactly equal to each other, the 75 current flowing from coil a¹ will flow through the second circuit only, and the current at the same time flowing from coil a² will follow the third circuit only.

Hence all the current flowing from both 80 coils a¹ and a², under these conditions, passes 85 through winding 8 of transformer G, causing alternating current to flow in a circuit which includes a condenser 7 and secondary winding 9 of transformer G. The current flowing 90 this circuit creates an alternating difference of potential between grid 11 and filament 12 of an electron tube K. Filament 12 is 95 constantly heated by a battery 13. Tube K may be used to control the vehicle V on which this tube is carried. An example of such control of a vehicle by tube K is shown and described in Letters Patent of the United States, No. 1,423,862, for railway traffic controlling systems, issued July 25, 1922, to Lloyd V. Lewis.

When the potentials induced in windings 100 a¹ and a² are equal and opposite to each other,

the currents flowing in the second and third circuits are also equal to each other, and create potentials in windings 4 of transformers F^1 and F^2 which are equal and opposite to each other, and hence no current flows through the fourth circuit which includes windings 4.

I will now assume that due to a broken rail no current is flowing in rail 1, but that the current flowing in rail 1^a returns to transformer T by some other path such, for example, as a rail of an adjacent track which is cross-bonded to rail 1. The potential induced in coil a^1 will, under this condition, send current through the first and second circuits. The current now passing through winding 3 of transformer F^1 induces a potential in winding 4 of transformer F^1 , which sends current through winding 4 of transformer F^2 . The current thus supplied to winding 4 of transformer F^2 induces in winding 3 of transformer F^2 a potential which helps the potential of coil a^1 to send current through the first circuit. On account of the potential thus induced in winding 3 of transformer F^2 , the current passing through winding 8 of transformer G will be reduced, and the more nearly the potential induced in winding 3 of transformer F^2 equals the potential of coil a^1 , the less will be the current flowing through winding 8 of transformer G.

If the current flowing through one of the rails of stretch Y is of lower magnitude than that flowing through the other rail, for example if the current flowing in rail 1 is less than that flowing in rail 1^a , the larger current thus induced in coil a^1 will cause a potential to be induced in winding 3 of transformer F^2 in opposition to the potential of coil a^2 , and will thus help reduce the current flowing through winding 8 of transformer G.

From the foregoing, it is evident that if the potential created in either of the coils a is less than that in the other coil, the current flowing through winding 8 of transformer G will be reduced by the action of transformers F^1 and F^2 .

Referring now to Fig. 2, vehicle V is here shown carrying two coils a^1 and a^2 wound on cores h , and transformer T supplies current to stretch Y adjacent point A exactly as in Fig. 1. In Fig. 2, however, each of the coils a is included in only one circuit, respectively. The circuit for coil a^1 includes winding 3 of transformer F^1 , a condenser 14, and winding 15 of transformer M^1 . When coil a^1 is energized, current is therefore supplied to winding 15 of a transformer M^1 , causing current to flow in a circuit including a condenser 7^a and secondary winding 16 of transformer M^1 . The current flowing in this circuit creates an alternating difference of potential between grid 17 and filament 18 of an electron tube L^1 . Filament 18 of tube

L^1 is constantly energized by a battery 19. Because of the alternating difference of potential between grid 17 and filament 18, alternating current is superimposed on the direct current which is supplied by battery 20 to the plate circuit for electron tube L^1 . This plate circuit passes from battery 20, through the primary winding 21 of a transformer H, and plate to filament of tube L^1 back to battery 20. Transformer H is provided with two primary windings, 21 and 22, each of which is connected to a terminal 28. When winding 21 is energized, as just described, an alternating potential is induced in secondary winding 23 of transformer H, which causes current to flow in a circuit including a condenser 7. An alternating difference of potential is thereby created between grid 11 and filament 12 of an electron tube K which, similarly to tube K in Fig. 1, controls the vehicle V on which tube K is carried.

Coil a^2 supplies current to a circuit which is similar to the circuit already described for coil a^1 , and which includes primary winding 3 of a transformer F^2 , a condenser 14, and primary winding 15 of a transformer M^2 . Transformer M^2 , by means of a circuit including a condenser 7^b and secondary winding 16, creates an alternating difference of potential between grid 17 and filament 18 of an electron tube L^2 . Alternating current is therefore superimposed on the direct current which is supplied by battery 20 to the plate circuit for tube L^2 . This plate circuit passes from battery 20, through winding 22 of transformer H, and plate to filament of electron tube L^2 back to battery 20.

The circuits are so arranged that at the instant the polarity of grid 17 of tube L^1 is positive the potential of grid 17 of tube L^2 is negative, when the current flows in opposite directions in rails 1 and 1^a . Therefore the magnetic flux produced by one of the windings 21 and 22 of transformer H decreases while the flux produced by the other of these windings increases, and hence the potentials created in winding 23 by these fluxes are added together.

If the current supplied by coil a^2 to transformer F^2 is of the same magnitude as the current supplied by coil a^1 to transformer F^1 , no current will flow in the circuit of the secondary windings 4 of these transformers, since the potentials created in these windings will then be equal and opposite.

If, however, the potential created in coil a^2 is less than that created in coil a^1 , then the potential created in winding 4 of transformer F^1 will be greater than that created in winding 4 of transformer F^2 , and hence the potential of winding 4 of transformer F^1 will cause a current to flow in opposition to the potential created in secondary winding 4 of transformer F^2 . This results in a smaller current being supplied to winding 15 of tube

transformer M^2 , and hence the current supplied to the plate circuit of tube L^2 will also be reduced, resulting in a lower energization of transformer H . In this way, current of lower magnitude will be induced in the circuit comprising condenser 7 and winding 23 of transformer H . As a result, a lower potential difference will be produced between grid 11 and filament 12 of tube K , resulting in an alternating plate circuit current of lower magnitude for tube K . If the potential induced in coil a^2 were still less, the alternating current which could flow in the plate circuit for tube K would clearly be still less.

If current should flow in the same direction and of the same magnitude in rails 1 and 1^a , the current supplied to winding 15 of transformer M^2 would be of the same magnitude and the same polarity as the current supplied to winding 15 of transformer M^1 , and hence the grids 17 of tubes L^1 and L^2 , respectively, would be of like polarity at all times, and hence the current supplied to the plate circuits for tubes L^1 and L^2 would be of equal magnitudes, and would be flowing at the same time in opposite directions through the windings 21 and 22 of transformer H , thus balancing each other, with the result that no current would flow in the circuit including secondary 23 of transformer H , and therefore there would be no difference of potential between grid 11 and filament 12 of tube K , and hence no alternating current could flow in the plate circuit for tube K .

From the foregoing description and the accompanying drawing, it will be understood that apparatus comprising my invention protects against false operation of train carried governing means by current flowing in one rail only or of lower magnitude in one rail than in the other rail, as in the event of a broken rail which is bonded to an adjacent rail of another track, or by current flowing in the same direction in the two rails, as in the event of a surge of the propulsion current on a railway on which the trains are electrically operated. Surges of propulsion current usually divide and flow in the two rails and in the same direction.

Although I have herein shown and described only two forms of railway traffic controlling apparatus embodying my invention, it is understood that various changes and modifications may be made therein within the scope of the appended claims without departing from the spirit and scope of my invention.

Having thus described my invention, what I claim is:

1. In combination, a stretch of railway track, means for so supplying said stretch with periodically varying current that at a given instant said current flows in one direction along one rail of the track and in the opposite direction along the opposite rail of

the track, a device in which current is induced by current flowing along said first rail, a second device in which current is induced by current flowing along said opposite rail, a first transformer, a second transformer, a circuit including the primary windings of said transformers and said first and second devices so connected in series that current induced in said first device by current flowing in one direction in said first rail opposes current induced in said second device by current flowing in the opposite direction in said opposite rail, a railway traffic control means so connected with said circuit as to complete a second circuit including said first device and the primary winding of said first transformer and to complete a third circuit including said second device and the primary winding of said second transformer, and a fourth circuit including the secondary windings of said transformers.

2. In combination, a stretch of railway track, means for supplying said stretch with current flowing in one direction along one rail at a given instant and with current flowing in the opposite direction along the opposite rail at the same instant, a device in which current is induced by current flowing along said first rail, a second device in which current is induced by current flowing along said opposite rail, a first transformer, a second transformer, a circuit including said first device and the primary winding of said first transformer, a second circuit including said second device and the primary winding of said second transformer, a third circuit including the secondary windings of said transformers, and railway traffic control means controlled by said first and second circuits.

3. In combination, a stretch of railway track, means for supplying said stretch with current flowing in one direction in one rail at a given instant with current flowing in the opposite direction in the opposite rail at the same instant, a device in which current is induced by current in said first rail, a second device in which current is induced by current in said opposite rail, railway traffic control means supplied with current by said first and second devices, and means operating when the current induced in one of said devices is reduced below the current induced in the other said device to reduce the current supplied to said control means by an amount more than that due to the reduction of the current supplied to said one device.

4. In combination, a stretch of railway track, means for supplying both rails of said stretch with current, a railway traffic control device in which current is induced by the current flowing in each of said rails, and means operating when the current in one of said rails is reduced below the current in the other said rail to reduce the current in said device by an amount greater than that due to

the reduction of the current in said one rail.

5. In combination, a stretch of railway track, means for supplying both rails of said stretch with current, a railway traffic control device, means for supplying said device with current which is controlled by the current flowing in each of said rails, and means operating when the current flowing in one of said rails is reduced below the current flowing in the other said rail to reduce the current in said device by an amount greater than that due to the reduction of the current in said one rail.

6. In combination, a stretch of railway track, means for supplying both rails of said stretch with current, vehicle control means carried on a vehicle and controlled by the current flowing in each of said rails, and auxiliary means controlled by the current flowing in each of said rails and operating when the current flowing in one of said rails is reduced below the current flowing in the other said rail to reduce the current supplied to said control means by an amount greater than that due to the reduction of the current in said one rail.

7. In combination, a stretch of railway track, means for supplying both rails of said stretch with current, vehicle control means carried on a vehicle and controlled by the current flowing in each of said rails, and two transformers controlled by the current flowing in said rails and operating when the current flowing in one of said rails is reduced below the current flowing in the other said rail to reduce the current supplied to said control means by an amount greater than that due to the reduction of the current in said one rail.

8. In combination, a stretch of railway track, means for supplying both rails of said stretch with current, a railway traffic control device controlled by current in both said rails, and means operating when the current in one of said rails is of lower magnitude than the current in the other of said rails to reduce the current supplied to said control means by an amount greater than that due to the lower magnitude of the current in the said one rail.

In testimony whereof I affix my signature.
GEORGE W. BAUGHMAN.
